DESIGN FOR A VANE PUMP

Warren R. Tucker, Dayton, Ohio, assignor to The Hydraulic Development Corporation, Inc., Mount Gilead, Ohio, a corporation of Delaware

Application August 10, 1942, Serial No. 107,869

Term of patent 14 years

To all whom it may concern:

Be it known that I, Warren R. Tucker, a resident of Dayton, in the county of Montgomery and State of Ohio, have invented a new, original, and ornamental Design for a Vane Pump, of which the following is a specification, reference being had to the accompanying drawings, forming a part thereof, wherein:

Figure 1 is a front perspective view of a vane pump, showing my new design;

Figure 2 is a side elevational view thereof;
Figure 3 is a front elevational view thereof;
and

Figure 4 is a plan view thereof.

I claim:

The ornamental design for a vane pump, substantially as shown.

WARREN R. TUCKER.
